UNITED STATES PATENT OFFICE.

ELIHU THOMSON, OF SWAMPSCOTT, MASSACHUSETTS.

REPAIRING RAILWAY-RAILS.

1,075,738.

Specification of Letters Patent. Patented Oct. 14, 1913.

Application filed May 26, 1913. Serial No. 769,949.

To all whom it may concern:

Be it known that I, ELIHU THOMSON, a citizen of the United States, residing in the town of Swampscott, county of Essex, State of Massachusetts, have invented an Improvement in Repairing Railway-Rails, of which the following is a specification:

The object of the present invention is to enable restoration of bearing surfaces of rails that may have become worn down by traffic in spots, and especially to restore or repair the surfaces at the ends of rails or at junctions thereof, or at cross-overs, frogs, etc., when, owing to continued traffic, such rail ends, etc., may have become battered down, deformed, or depressed so as to cause excessive bumping at joints of such rails or frogs, and the like; a common experience, especially on street railways, and a defect which is always tending to accentuate itself if not soon repaired. Ordinary methods of repair, such as replacement of worn rails, cutting off the worn ends and replacement of the so shortened rails, often entails excessive expense owing to the fact that the roadway itself has to be dug up for the renewals, or for the shifting of the shortened rails so as to again bring them into line end to end.

It is the aim of my present invention to avoid this delay and expense, attended as it is with serious interruption to traffic, by repairing the rail surfaces preferably *in situ*, though the methods of my invention may also be applied to restore the bearing surfaces of rails that have been taken up preparatory to re-laying them, but in the latter case it is not so important, as the worn parts may often be best cut out.

Although with sufficient pressure properly applied by my means provided, the repair desired may be made on cold rails, I prefer to apply local heating means to the part of the rail structure which has been worn or depressed so as to raise the temperature of the particular part concerned to a sufficient degree to render the same plastic under pressure, and then either simultaneously with the heating, or immediately subsequently thereto and before cooling has taken place, I apply mechanical pressure laterally to the rail head or surface, or below it, to pinch it, so to speak, upwardly, and so elevate the top surface or bearing surface to its original place or level or a little beyond, after which,

if necessary, a local grinding to a small amount brings the surface upon which the wheels run to a substantially right line or plane corresponding to that of the adjacent parts of the rail to those treated. In the present invention I have illustrated fluid pressure means for applying mechanical pressure laterally to the rail head or surface. For the local heating I may apply electric current, or electric heating in any of its forms, or I may use blow-pipes with air or oxygen blast under pressure, with rich fuels, such as hydrogen, acetylene, hydrocarbon gas or oil vapors. For the mechanical forging pressure I may use hydraulic or screw jacks, where such may be most conveniently applied; but as above referred to, I have preferred to illustrate fluid pressure means, such as hydraulic means for applying the lateral pressure for forging. The operation as a whole may be employed with the rails remaining in place in the roadbed and with a minimum removal or disturbance of the paving or road material adjoining the repaired surface.

My invention is illustrated in the subjoined drawings accompanying this specification and of which

Figure 1 represents a condition of rail surface commonly found before repair; Fig. 2 a rail section corresponding thereto; Fig. 3 represents the application of hydraulic pressure laterally to the rail head while the rails are cold or subsequently to the heating of the worn section of the rail with blow-pipes; Fig. 4 represents the preferred form of my invention in which electrical heating means for heating the rail locally are combined with the hydraulic means for applying pressure laterally to the rail head; Fig. 5 represents a section taken on the line 5—5, Fig. 4; Fig. 6 shows the rail as restored after the operation of applying pressure laterally thereto to press metal from the rail upwardly toward its tread; Fig. 7 the condition after thus treating the rail and the subsequent grinding thereof by a guided grinding wheel; Fig. 8 shows a mode of applying heat by blowpipes where such heating means is used, and before applying the pressure clamps illustrated in some of the previous figures.

In all the figures of the drawing like figures represent like parts.

In Fig. 1,—1 and 2 indicate parts of meeting rails, or rail ends in abutment, and at 3 a hollowed, battered or depressed part of the rail head or bearing surface say, of rail 5 1. It is more or less below the general line 4—4 of the true rail or original contour. In Fig. 2, the end section of rail end 1 at the dotted vertical line, Fig. 1 is indicated and the upper horizontal full line, Fig. 2, indicates the original surface. In Fig. 3 the 10 same rail section is seen clamped by the head only, between two heavy pieces 5 and 6; one on the outside of the rail and the other on the inside thereof.

15 By means of the construction shown in Fig. 3, after the worn section of the rail head has been heated by means of blowpipes, such as shown in Fig. 8, if the clamps 5 and 6 be pressed strongly together the metal of 20 the rail is compressed and rises between them being prevented from moving downward by the web 11 of the rail below and as usual the presence of the fish plates 12 and 13 indicated. The form of the jaws or 25 clamps is made such as to favor this result. The clamp 6 must be prevented from moving with respect to the rail as by locking it over the inner edge of the tread as at 39 or 30 making it extend more along the length of the rail than does the clamp 5, or both. The clamp 5 therefore is the part which moves relatively to the rail position and so effects the restoring the rail surface without disturbing the inner line of the rail head. This 35 is indicated in the plan, Fig. 5, where the clamps are shown in section above the rail itself.

While I have referred to the construction Fig. 3 as being utilized after the worn section of the rail head has been heated by 40 means of blowpipes it will be understood that if sufficient pressure were applied to the clamps 5 and 6 in a lateral direction with respect to the head of the rail, metal there- 45 from could be raised upwardly from the latter to restore the worn surface thereof while the rail was cold. I prefer however to heat the rail prior to applying the pressure clamps or simultaneously therewith as by 50 means of the electrical forging machine illustrated in Fig. 4.

In Fig. 4 I have combined with the hydraulic means for applying pressure to the clamps 5 and 6 an electrical forging device 55 mounted in coöperative relation therewith in order that the heating of the rail and the application of pressure laterally may be performed either simultaneously or by independent operations as desired, but the mechanism being combined in a single operative 60 structure. This electrical forging device comprises essentially a transformer of the low voltage type, the primary coil of which is suspended by means of a boom or sup- 65 port on the frame of the machine, the low

voltage secondary coil being hung upon and embracing the primary. In this case the secondary terminals extend into and constitute the abutting ends of the clamps where the latter engage the rail head. This type 70 of machine furnishes a heavy electric current to the electrodes or clamps 5 and 6. If these electrodes be pressed together, by means of the pressure device illustrated, simultaneously with the passage of heavy 75 electric currents through the electrodes and rail section to be heated or immediately subsequent to said heating, the metal of the rail is compressed and rises between the electrodes or clamps in the manner referred to 80 heretofore.

In Fig. 3, it will be seen that with my improved apparatus it is necessary to remove a very small portion from the road bed 7 in the immediate neighborhood of the clamps 5 85 and 6, the road surfacing being illustrated at 8, 9, etc. This is quite a decided advantage over the necessity heretofore experienced of having to tear up considerable of the road-bed in order to make a repair, with 90 the accompanying inconvenience to traffic in the vicinity. In this figure, 10 represents the head of the rail, 11 the web, 12 and 13 the usual fish-plates, 14 and 15 the usual bolts therethrough, etc. The clamps 5 and 95 6 are carried by a supporting frame 16, suitably mounted upon a truck (not shown), in operative relation with the rails to be repaired. The repairing device may also have a movement on the truck transversely of the 100 length of the rails; that is, sidewise, in order that after a repair has been made upon one rail it may be readily moved to be applied in operative relation with the parallel rail. The clamps 5 and 6 are pivotally 105 secured to the link 17 of the frame 16 by means of the fulcrum studs 18 and 19. The upper portion of the frame 16 has mounted upon it or suitably formed therein a cylinder 20 which may be utilized for the reception 110 of fluid under pressure from a suitable source of hydraulic supply or for the reception of compressed air, depending upon which fluid is chosen for the operating means. The pipe 21 connects the cylinder 115 20 with the source of fluid supply, the said source not being shown in the drawing. A suitable regulating valve 22 is provided upon the pipe 21 for the purpose of regulating the supply of operating fluid to the 120 cylinder 20.

In the construction shown in Fig. 4 wherein an electrical forging device is combined with the clamp operating means, the primary coil 23 is mounted upon the link 17, being suitably electrically insulated therefrom by the insulating piece 24, 25. The secondary coil 26 is hung upon or embraces the primary coil 23, and the coil 26 has flexible secondary terminals 27 and 28 which extend 130

into and are connected with the clamps 5 and 6 at 29, 30 and 31, 32 respectively so as to intervene between the rail head and the clamps 5 and 6. For the purpose of application of my invention to different forms of rail head, the ends or rail engaging faces of the electrodes 30 and 31 are provided in separate or removable pieces, these pieces having the particular form or contour desired to match the particular form of rail head being repaired. They may be of hardened steel, or any other suitable metal which will not be itself injuriously affected for the purpose by the high temperature generated by the heavy electric current conveyed to the rail head. The pieces are thus made easily removable in order that they may be exchanged for others of different form or shape, and for the purpose of permanently fastening them in place during the operation of repair they are connected to the clamps by means of the bolts 33 and 34 the latter being suitably insulated from the surrounding metal of the clamps as shown in Fig. 5. In the case of the clamp 6, the removable rail engaging faces are insulated from the clamp or electrode proper, by means of insulation 36, 37.

In Fig. 5, it will be seen that the clamp 6 has a greater extent in parallel relation with the inner line of the rail, than has the clamp 5 with the outer line thereof. This construction constitutes clamp 6 substantially an anvil and renders it relatively immovable with respect to clamp 5. This differential area of the clamps permits of the inner line of the rail head being maintained in its original form. This effect, it will be readily seen, is very essential where it is necessary to preserve the original wheel gage intact.

Fig. 6 will indicate the form taken by the rail head under the treatment of my invention, the dotted lines showing the form before the treatment was begun. The wheel bearing surface or tread will be seen to be raised or bulged upward. If skilfully done this restores the top surface to its original plane, or a little beyond. In the latter case the slight excess of metal lifted may be removed by traversing the upper surface by a guided grinding wheel as is usual in such cases. The result is indicated in Fig. 7, where it will be seen that the metal so restored to the tread is in reality, as it were, taken from the outer part of the head, reducing its width somewhat. This process may be again repeated when the rail wears a second time, and again and again repeated, and the form of the outer clamp 5, Fig. 5, may be made so as to actually lift metal from under the head so that the form of the section at last becomes as indicated in dotted lines, Fig. 7. When this has become the case the further life of the rail end can

again be prolonged by electrically welding to the outside of the rail head a strip of metal in place of the deficiency so caused, but as that is no part of the present invention it will not be necessary to describe it, 70 as it is moreover like an ordinary case of electric welding.

While I have described the preferred form of my invention as being a device of the type illustrated in Fig. 4 it will be understood that it is possible to carry out the object of my invention by somewhat different methods and for this reason I have illustrated the application of separate heating means for heating the rail head before applying the pressure clamps of Fig. 3. Such heating means is illustrated in Fig. 8, wherein it is shown that for heating of the rail head a set of blowpipes may be used with combustible gas or vapor and with an air blast or one 80 of oxygen or a mixture of air and oxygen. The blowpipe illustrated in this figure may be of the type to be held by hand or it may be provided with a suitable support which embraces or rests upon the rail. While I 90 have illustrated only one blowpipe 38 in the figure it is conceivable that in practice a multiple of blowpipes might be used alongside with their flames so concentrated upon the worn spot or section as to rapidly 95 heat the latter to the desired point for working. Such blowpipes of sufficient power are already known in the art of heating metal locally, as in local annealing of armor plate and the like. They are generally jacketed 100 with fireproof heat non-conductor forming a heating chamber close to the metal surface, so preventing radiation and at the same time localizing and concentrating the heating effect to the part desired to be worked. As soon as such a temperature of the rail head as renders it plastic is reached the blowpipes are removed and the set of clamps forcibly moved together, as in Fig. 3, is applied quickly to finish the work of 110 raising metal from the rail to restore the worn surface thereof.

The means of repair of my invention, it will be evident to those skilled in the art, may be used without substantial differences 115 to frogs when worn, or to other rail structures. They may also be applied to the restoration and repair of similar structures ordinarily incapable of being handled or otherwise treated.

The particular merit of my present invention is that it allows restoration of surfaces and prolongation of wearing portions of rails and the like *in situ*, or without disturbing the road-bed to any considerable extent, 125 and so saves large expense for repairs and renewals as ordinarily made.

In accordance with the provisions of the patent statutes, I have described the principle of operation of my invention, together with 130

the apparatus which I now consider to represent the best embodiment thereof; but I desire to have it understood that the apparatus shown is only illustrative and that the 5 invention can be carried out by other means.

What I desire to secure by Letters Patent of the United States is:

1. The method of repairing and restoring worn surfaces of railway rails which consists in laterally pressing and raising a portion of the rail toward its tread by applying pressure to the outer side of the rail head and maintaining undisturbed the inner or wheel flange engaging surface of the rail head.

2. The method of repairing and restoring worn surfaces of railway rails which consists in laterally pressing and raising metal by applying pressure to a restricted area of 10 the outer side of the rail head and supporting a relatively greater area of the inner or wheel flange engaging surface of the rail in 20 the line of application of such lateral pressure for preserving unaltered the said surface.

3. An apparatus for repairing the worn section of a railway rail head having, in combination, means for heating the section of the rail head, and means for laterally 30 pressing and raising the heated section having provision for maintaining undisturbed the original inner line of the rail head.

4. An apparatus for repairing the worn section of a railway rail head having, in combination, means for heating the section of the rail head, an anvil, a pressure tool, and means for forcing together the pressure 35 tool and anvil.

5. An apparatus for repairing the worn 40 section of a railway rail head having, in combination, electrodes engaging both sides of the rail section, one of said electrodes constituting an anvil for maintaining the inner line of the rail head undisturbed and the 45 other electrode constituting a pressure tool, and means for forcing the pressure tool toward the anvil to restore metal to the worn surface of the rail head.

6. An apparatus for repairing the worn 50 section of a railway rail head, having in combination, an anvil for engaging the inner surface of the rail head and maintaining undisturbed the original inner line of the rail head, and a pressure tool for engaging the 55 outer surface of the rail head opposite the anvil, said anvil and pressure tool having removable rail engaging faces adapted to be removed and exchanged for rail engaging

faces of different shape to conform to different shapes of rail head. 60

7. An apparatus for repairing the worn section of a railway rail head, having in combination, electrodes engaging opposite sides of the rail head for heating the worn section, one of said electrodes engaging the 65 inner surface of the rail head and serving as an anvil for maintaining undisturbed the original inner line of the rail head and another of said electrodes engaging the outer surface of the rail head and serving as a tool 70 for setting up the heated section, said anvil and setting up tool having removable rail engaging faces adapted to be removed and exchanged for rail engaging faces of different shapes to conform to different shapes 75 of rail head.

8. An apparatus for repairing the worn section of a railway rail, having in combination, relatively movable electrodes for engaging opposite sides of the worn section of 80 the rail head, means for supplying current to the electrodes for heating the worn section, and means for relatively moving the electrodes toward each other to restore the worn section. 85

9. An apparatus for repairing the worn section of a railway rail, having in combination, a pressure tool engaging the outer edge of the tread where worn for laterally and upwardly pressing metal from the rail to 90 toward its head or tread, an anvil opposite the pressure tool and engaging the inner line of the tread or head for a greater length than the pressure tool engages the outer surface thereof, and means for relatively forcing the 95 pressure tool and anvil together.

10. An apparatus for repairing the worn section of a railway rail, having in combination, electrodes engaging opposite sides of the worn section of the rail head, means for 100 supplying current to the electrodes for heating the worn section, the electrode which engages the outer surface of the rail head serving as a pressure tool and the electrode which engages the inner surface of the rail 105 head serving as an anvil and engaging a greater length of the rail head than the pressure tool, and means for relatively forcing the two electrodes together to restore the worn portion of the rail head. 110

In testimony whereof I have affixed my signature, in presence of two witnesses.

ELIHU THOMSON.
